(57) **CLAIM**

The ornamental design for a paint can sealer bag, as shown and described.

DESCRIPTION

FIG. 1 is a front view of a paint can sealer bag showing my new design;

FIG. 2 is a rear view of the paint can sealer bag;

FIG. 3 is a right side view of the paint can sealer bag;

FIG. 4 is a left side view of the paint can sealer bag;

FIG. 5 is a top view of the paint can sealer bag;

FIG. 6 is a bottom view of the paint can sealer bag; and,

FIG. 7 is a top front side perspective view of the paint can sealer bag.
The broken lines in FIG. 7 are illustrative of environmental structure forming no part of the claimed design.
